COILING APPARATUS FOR METAL STRIP

Mathias Langen, Parkstone, England, assignor to The Loewy Engineering Company Limited, London, England, a British company

Application July 22, 1953, Serial No. 369,604

Claims priority, application Great Britain July 31, 1952

10 Claims. (Cl. 242—78.4)

The coiling of strip in modern continuous strip rolling mills presents a number of problems which are mainly due to the high speeds at which the strip issues from the mill and also to the great weight of coils to be handled.

A type of coiler generally in use for coiling hot strip comprises a number of guide rollers which are distributed around a centrally disposed driven mandrel and backed by pressure means urging them towards the center of the mandrel. The guide rollers are further supported on retractable carriers, so that the guide rollers can gradually recede as the coil is built up. The initial position of the guide rollers relative to the mandrel is adjustable so that the radial clearance between the guide rollers and the mandrel can be varied in accordance with the thickness of the strip to be coiled. The mandrel of such a coiler is collapsible in order to enable the finished coils to be discharged, and comprises, to this end, a number of segments which are movable relative to a core which forms the center portion of the mandrel.

These coilers are operated in such a way that the guide rollers are pre-set at a distance from the mandrel so that the radial clearance between them and the mandrel is somewhat larger than the thickness of the strip to be coiled. The coiler is then started with the mandrel rotating at a linear speed, preferably slightly higher than the delivery speed of the strip. A length of strip is then fed in a substantially tangential direction into and along the circular space formed between mandrel and guide rollers. Due to the centrifugal action to which it is subjected whilst travelling in the space, the strip will be urged in close contact with the guide rollers. These will deflect the strip as it passes by, into a circular shape, and thus form the first layers of the coil.

It is mainly during this stage of the coiling operation that the shortcomings of existing coilers have become apparent. These are due to the following causes:

As the strip travels along the gap, the guide rollers are successively pushed aside to make room for the strip. The movement imparted to the guide rollers is an instantaneous one involving a rapid acceleration of the rollers, as well as of their carriers. This acceleration in turn produces inertia forces which cause the guide rollers to rebound back and forth with great violence whilst the strip passes by. This results in the leading end of the strip being hammered into those portions of the strip intermediate the leading end and the guide rollers as the mandrel is non-resilient and therefore acts like an anvil. In this way, indentations or kinks are formed in the first few layers of the strip, although with gradually decreasing depth. Further hammering of the strip takes place each time one of the guide rollers rides over such a kink.

This intense and repeated hammering action of the guide rollers is liable to mar the strip to a considerable extent so that its forward end has often to be scraped. Moreover, the hammering increases materially the wear on the guide rollers and their carriers and, in particular, their pivotal links whereby the need for maintenance is correspondingly increased.

2

Damage to the strip is likely to be particularly heavy in those cases where the strip is considerably narrower than the mandrel and the guide rollers. The area of the strip which is subjected to the hammering forces is then comparatively small, and the specific impact load on the strip thereby correspondingly increased.

The sharp kinks hammered into the strip, apart from marring its surface, have the additional disadvantage of hindering the leading end of the strip from sliding forward relative to the next layer of the coil. If this movement of the leading end is impeded, the tight wrapping of the strip around the mandrel becomes uncertain and difficult, and the strip may slip on the mandrel. If this occurs after the guide rollers have been withdrawn, the building-up of the coil may suffer in as much as its individual layers are axially displaced relative to each other, or, in other words, telescoped.

It is an object of the present invention to provide an improved coiling apparatus for metal strip comprising 20 guide rollers which are distributed around a centrally disposed mandrel and which are urged towards the axis of the mandrel, and in which the various shortcomings set forth in the foregoing are avoided.

Several forms of the invention will now be described 25 by way of example with reference to the accompanying drawings in which:

Fig. 1 is a diagrammatic illustration of a coiling apparatus according to the prior art,

Figs. 2 to 5 inclusive are sections through one form 30 of a coiler according to this invention, in various stages of a coiling operation,

Fig. 2 showing the coiler empty and at rest,

Fig. 3 at the beginning of a coiling operation,

Fig. 4 towards the end of a coiling operation,

Fig. 5 after termination of a coiling operation, with a coil ready for discharge from the coiler,

Fig. 6 is an axial section through the coiler of Figs. 2 to 5, along the line VI—VI of Fig. 2,

Fig. 7 is a partial axial section through the coiler of 40 Figs. 2 to 5, along the line VII—VII of Fig. 2,

Figs. 8 and 9 are radial sections through another embodiment of the coiler according to the invention, showing its mandrel at different stages of its operation,

Fig. 8 showing the mandrel at rest,

Fig. 9 at the beginning of the coiling operation,

Figs. 10, 11 and 12 are radial sections through a still further embodiment of a coiler according to the invention, showing its mandrel at different stages of its operation,

Fig. 10 showing the mandrel at rest and with the shoes not expanded,

Fig. 11 showing the mandrel at rest, with the shoes expanded,

Fig. 12 showing the mandrel during its rotation.

The coiler shown in Figs. 2 to 7 inclusive is substantially of the same type as that of Fig. 1, the parts 15, 16, 17, 19 and 20 being common to both coilers and having the same arrangement and function. As in the case of Fig. 1, several components of the coiler, which are of minor importance, are not shown.

In these figures the centrally disposed driven mandrel is indicated at 15 the retractable guide rollers are illustrated at 16. The segments 19 by which the mandrel 15 may be collapsed to permit removal of the finished coil 65 therefrom are mounted around a central core 17. Expansion of the segments 19 is effected by wedge shaped spreaders 20 which can be entered between adjacent segments 19. All these parts are of conventional construction well known in the art and are illustrated, for example, in United States Patent No. 2,693,919.

The mechanism for expanding and collapsing the seg-

ments 19 with the aid of the spreaders 20, is shown more in detail in Fig. 6.

The spreaders which extend along the segments have at their under-sides a series of cams 27 of substantially saw-tooth shape adapted to engage similarly shaped cams 28 on axially movable racks 29. The latter can be moved simultaneously through a common crosshead 30 and an actuating rod 31 which passes through the mandrel 15 to a point outside the coiler for the attachment of mechanical or automatic operating means, not shown here. To enable the segments 19 to collapse, the actuating rod 31 is moved to the right in Fig. 6 whereby the cams 27 and 28 are disengaged from each other and the spreaders 20 freed to drop back into inoperative positions. It is to be understood that the means for actuating the segments can have any other suitable form than that shown and described here.

In accordance with the present invention, the coiler of Figs. 2 to 7 has a number of shoes 25 arranged in slots 25a at the periphery of the segments 19 of the mandrel. These shoes are of comparatively light weight and are therefore capable of yielding readily to centrifugal action upon rotation of the mandrel 15. Normally, the shoes are seated in their slots and held in non-protruding position relative to the mandrel by such means as light springs 43 which are in engagement with headed pins 44 (Fig. 7).

The shoes 25, when subjected to centrifugal action, are flung out from their seats in protruding positions relative to the mandrel 15. Their radial movement is limited by stop rings 26 (Fig. 6), arranged at either end of the mandrel and attached to parts 34 and 36, which are separate from the segments 19 and, therefore, do not take part in their expansion or collapse. The stop rings 26 project axially over shouldered ends of the shoes and the latter are, when in non-protruding position, spaced apart from the rings by a distance corresponding to the permissible outward travel of the shoes under centrifugal action.

The rings or stops 26 are here so arranged that they arrest the flung-out shoes 25 in a radial position which corresponds to that taken up by the segments 19 upon their expansion. Thus the flung-out shoes and the expanded segments can form together a continuous cylindrical surface on which the strip is wound up as coiling progresses.

The part 34, to which the lefthand ring or stop 26 is attached, is secured by means of bolts 33 to the core part 17 of the mandrel and terminates in a hollow driving shaft 32 for the mandrel supported in a housing 35. The part 36, to which the righthand ring 26 is attached, is in the form of a drum which forms a continuation of the mandrel and covers the outwardly projecting parts of the mandrel.

In order to prevent the segments 19 from yielding to centrifugal action and thus becoming prematurely expanded, springs 37 are provided (Fig. 6), which tend to draw the segments 19 towards the core part 17 of the mandrel. These springs are housed in flanged casings 38 seated in the segments 19 and held in compression by headed bolts 40 which are threaded into the core part 17. The parts 37, 38 and 40 are accommodated in radial bores of the segments 19 which are covered by bars 41, so as to avoid any marking of the strip, the latter being clamped down on to the segments by means of straps 42. The springs 37, in addition to preventing a premature expansion of the segments 19, aid in the collapse of these segments after the spreaders 20 have dropped back.

The coiler according to Figs. 2 to 7 is operated as follows:

After the guide rollers 16 have been preset at such a distance from the mandrel 15 that the radial gap between these rollers and the mandrel is slightly larger than the thickness of the strip to be coiled, the coiler is started up, a linear speed being imparted to the coiler which is a little higher than that of the strip. A length of strip S

is then entered in a substantially tangential direction into the radial gap between the guide rollers 16 and mandrel 15 through suitable channels or other guide means (not shown here). Whilst travelling in this gap, the strip is subjected to centrifugal forces, which carry the strip into close contact with the guide rollers 16, whereby the strip is deflected so as to form convolutions around the mandrel, the pressure acting on the guide rollers from behind ensuring that this contact is maintained so long as the guide rolls are in position.

During this stage of operation—illustrated in Fig. 3—the shoes 25 are flung out by centrifugal action until their shouldered ends meet the rings 26, whilst the segments 19 are kept for the time being in their collapsed position. The shoes protrude then over the surface of the segments 19, thus forming the only supports for the strip within the interior of the coil. As the shoes are of relatively light weight, they can yield to a certain extent, if pressed inwards. The support given to the strip by the shoes is therefore of an elastic nature, and any impacts coming from the guide rollers will be cushioned and their hammering action, together with all its detrimental consequences, eliminated.

As will be seen from Fig. 3, the shoes 25 are gradually forced back towards their seats by the wrapping action of the strip. After the first few layers of a coil have been formed in this manner, the segments 19 are expanded by means of the spreaders 20 and will form then with the flung-out shoes 25 a continuous cylindrical surface on which the strip is supported during the further progress of the coiling operation, the shoes being firmly reseated in their slots. This stage of the operation is shown in Fig. 4. As no sharp kinks are formed in the strip, its leading end can slide forward without any difficulty after expansion of the segments, whereby a tight wrapping of the strip around the mandrel is assured, and the danger of the layers of the coil being telescoped is avoided.

After the strip has been tightened on to the mandrel consequent on the expansion of the segments, the guide rollers 16 are retracted. Coiling is continued until the length of strip is wound up, with the coiling torque being transmitted on to the strip by the mandrel. The coiler is then stopped and the segments 19 caused to collapse after retraction of the spreaders 20, so that the finished coil can be axially removed from the coiler in the usual manner by such means as a stripper-plate, not shown here.

The coiler according to Figs. 8 and 9 is generally similar to that described before, in so far as it comprises a number of guide rollers, not shown here, corresponding to the rollers 16 of the embodiment according to Figs. 2 to 7. The coiler is further equipped with a mandrel 115 consisting of a core part 117 and segments 119, the latter being adapted to be expanded by means of spreaders 120 and movable racks 129. Shoes 125 similar to the shoes 25 previously described are arranged in slots at the periphery of the segments 119 in a manner which allows the shoes to be flung out by centrifugal action, suitable means, not shown, and corresponding to the rings 26, being provided for limiting the outward movement of the shoes 125. These stop means are so arranged that they will arrest the outward movement of the shoes 125 only after their radial distance from the centre of the mandrel 115 is greater than that of the expanded segments 119. The shoes, when flung out by centrifugal action, will thus protrude over the surface of the expanded segments. This makes it possible for the segments 119 to be expanded before a length of strip is entered into the coiler and even whilst the mandrel is still at rest, as shown in Fig. 8.

Upon rotation of the mandrel 115, the shoes 125 are flung out in the same way as the shoes 25, leaving their seats in the slots, so that they can act as elastic supports for the strip during the formation of the first layers of the coil. This stage of operation is shown in Fig. 9. As coil-

ing progresses, the shoes 125 are gradually forced back on to their seats due to the wrapping action of the strip. The latter is thereby firmly tightened on to the mandrel which can then transmit the coiling torque during the remainder of the coiling operation, the guide rollers being retracted as in the case of the coiler according to Figs. 2 to 7.

After coiling is terminated, the segments 119 are collapsed upon actuation of the spreaders 120, so that the coil can be removed from the mandrel in an axial direction as usual.

The mode of operation of the coiler according to Figs. 8 and 9 has certain advantages over that of the coiler according to Figs. 2 to 7. In the latter case, it is necessary for the expansion of the segments to be timed rather closely with respect to the build-up of the first layers of the coil. In the former coiler, this is not required as the segments can be expanded before rotation of the mandrel begins. For the same reason, the coiler according to Figs. 8 and 9 does not have to have means preventing premature expansion of the segments due to centrifugal action, and the springs corresponding to the springs 37 of the coiler according to Figs. 2 to 7, if provided, can be made considerably weaker, or left out altogether.

The coiler according to Figs. 10 to 12 has no collapsible segments, and its mandrel 215 is formed by a non-expandable drum, shoes 225 of T-shaped section being accommodated in slots at the periphery of that drum. These shoes can be flung out under centrifugal action upon rotation of the mandrel 215 whereupon they leave their seats and can then act as elastic supports for the strip in the same manner as the shoes 25 and 125. Associated with the shoes 225 are mechanical means for expanding them, the means comprising axially extending bars 229, taking the place of the racks 29 of Fig. 6. Both the shoes and the bars are formed with cams of saw-tooth shape, corresponding to the cams 27 and 28 respectively. The bars 229 may be actuated by means similar to those provided for the actuation of the racks 29. The coiler is also equipped with guide rollers, not shown here, which are similar to those described before as regards their arrangement and function.

When this coiler is at rest, as shown in Fig. 10, its shoes 225 are in their innermost position. Before coiling is started, the shoes 225 are expanded by means of the bars 229 as shown in Fig. 11. Upon rotation of the mandrel 215, the shoes are flung out under centrifugal action leaving their seats in the slots and acting as elastic supports for the strip. This stage of operation is shown in Fig. 12. Whilst coiling is in progress, the shoes 225 are gradually forced back on to their seats, due to the wrapping action of the strip, whereby the strip is firmly tightened to the shoes 225 and the coiling torque transmitted by them, the guide rollers being retracted as soon as the tight wrapping of the strip has been accomplished. After coiling is terminated, the bars 229 are actuated and the shoes 225 thus allowed to collapse; the coil can then be removed from the mandrel 215 in an axial direction, as usual.

The T-section of the shoes enables an almost continuous cylindrical surface to be formed by the shoes alone.

The coiler according to Figs. 10 to 12 has the advantage of a comparatively simple design, due to the absence of segments. This makes it possible to increase the thickness of the driving shaft for the mandrel so that deflections of the latter, due to bending loads, can be greatly reduced. This again obviates the necessity for an outboard bearing for the mandrel in many cases where such a bearing would otherwise have to be provided.

It will be understood that the invention is capable of other embodiments. Variations can, for instance, be made in the arrangement of the shoes and in the means

for limiting their outward movement, as well as in numerous other respects.

What is claimed is:

- 5 1. A coiling apparatus for metal strip, comprising a centrally disposed driven mandrel having slots through the periphery thereof, retractable guide rollers arranged around said mandrel for guiding a strip to be coiled, and elements disposed on the mandrel around its periphery and extensible through said slots in the periphery of said mandrel, said elements yielding to centrifugal action upon rotation of said mandrel whereby they are flung out towards said guide rollers and contact the metal strip being coiled on said mandrel.
- 10 2. A coiling apparatus for metal strip, comprising a centrally disposed driven mandrel having slots therein, retractable guide rollers arranged around said mandrel for guiding a strip to be coiled, and shoes arranged at the periphery of said mandrel and extending through said slots in the periphery of said mandrel, said shoes yielding to centrifugal action upon rotation of said mandrel whereby they are flung out towards said guide rollers and contact the metal strip being coiled on said mandrel.
- 15 3. A coiling apparatus for metal strip, comprising a centrally disposed driven mandrel having slots therein, retractable guide rollers arranged around said mandrel for guiding a strip to be coiled, and shoes normally seated in slots arranged at the periphery of said mandrel and extending through said slots in the periphery of said mandrel in a direction substantially parallel to the axis of said mandrel, said shoes yielding to centrifugal action upon rotation of said mandrel, whereby they are flung out from their seats in said slots towards said guide rollers and contact the metal strip being coiled on said mandrel.
- 20 4. A coiling apparatus for metal strip, comprising a centrally disposed driven mandrel having slots therein, retractable guide rollers arranged around said mandrel for guiding a strip to be coiled, and shoes normally seated in slots arranged at the periphery of said mandrel and extending through the strip supporting surface the periphery of said mandrel in a direction substantially parallel to the axis of said mandrel, said shoes yielding to centrifugal action upon rotation of said mandrel, whereby they are flung out from their seats in said slots toward said guide rollers and project beyond the periphery of said mandrel and into contact with the strip being coiled, said shoes being of such a height that they do not protrude beyond the surface of said mandrel when in their seated position.
- 25 5. A coiling apparatus for metal strip, comprising a centrally disposed driven mandrel having slots through the periphery thereof, retractable guide rollers arranged around said mandrel for guiding a strip to be coiled, and shoes seated in slots arranged at the periphery of said mandrel and extending in a direction substantially parallel to the axis of said mandrel, said shoes yielding to centrifugal action upon rotation of said mandrel, whereby they are flung out from their seats in said slots towards said guide rollers, said shoes being of such a height that they protrude over the surface of said mandrel when in their seated position.
- 30 6. A coiling apparatus for metal strip, comprising a centrally disposed driven mandrel having slots through the periphery thereof, retractable guide rollers arranged around said mandrel for guiding a strip to be coiled, elements disposed on the mandrel around its periphery and extending through the strip supporting surface of the periphery of said mandrel, said elements yielding to centrifugal action upon rotation of said mandrel whereby they are flung out towards said guide rollers beyond the periphery of said mandrel, and stops for arresting the outward movement of said elements.
- 35 7. A coiling apparatus for metal strip, comprising a centrally disposed driven mandrel having slots through the periphery thereof, retractable guide rollers arranged around said mandrel for guiding a strip to be coiled, shoes

arranged at the periphery of said mandrel and extending through the periphery of said mandrel in a direction substantially parallel to the axis of said mandrel, said shoes yielding to centrifugal action upon rotation of said mandrel whereby they are flung out beyond the periphery of said mandrel towards said guide rollers and into contact with the strip being coiled, and stops for arresting the outward movement of said shoes, said stops being in the form of rings which project axially over the ends of said shoes, said shoes when at rest being spaced apart from said rings by a distance corresponding to the permissible outward travel of said shoes.

8. A coiling apparatus for metal strip, comprising a centrally disposed driven mandrel composed of a number of expandable segments having slots therein, means for expanding said segments, retractable guide rollers arranged around said mandrel for guiding a strip to be coiled, and elements disposed on said mandrel segments and around their periphery and extending through their periphery, said elements yielding to centrifugal action upon rotation of said mandrel whereby they are flung out beyond the periphery of said segments towards said guide rollers and into contact with the strip being coiled.

9. A coiling apparatus for metal strip, comprising a centrally disposed driven mandrel composed of a number of expandable segments having slots therein, means for expanding said segments, retractable guide rollers arranged around said mandrel for guiding a strip to be coiled, a number of elements disposed on said mandrel segments and around their periphery and extending through their periphery, said elements yielding to cen-

trifugal action upon rotation of said mandrel whereby they are flung out beyond the periphery of said segments towards said guide rollers and into contact with the strip being coiled, and means for preventing premature expansion of said mandrel segments due to centrifugal action.

10. A coiling apparatus for metal strip, comprising a centrally disposed driven mandrel composed of expandable segments having slots therein, means for expanding said segments, retractable guide rollers arranged around said mandrel for guiding a strip to be coiled, elements disposed on said mandrel segments and around their periphery and extending through their periphery, said elements yielding to centrifugal action upon rotation of said mandrel whereby they are flung out beyond the periphery of said segments towards said guide rollers and into contact with the strip being coiled, and spring means for preventing premature expansion of said mandrel segments under centrifugal action.
